ENCLOSED CAKE TRAY

Ben Elwood White and John A. Cushman, Jr.,
Reedsville, and Andrew A. Dukert, Upper Darby,
Pa., assignors to American Viscose Corporation,
Wilmington, Del., a corporation of Delaware

Application April 4, 1950, Serial No. 153,778

2 Claims. (Cl. 206—72)

1

The present invention relates to containers for storing and protecting a plurality of similar articles in which they may await further treatments and particularly to trays or the like which are adapted to support a number of strand packages such as cakes of rayon yarn.

In the manufacture of rayon yarn, particularly in the process based on acid regeneration of cellulose from a viscose solution, the yarn is centrifugally collected in the form of "cakes" of annular shape which are doffed from the spinning buckets onto trays or conveyors and transferred to a washing station. After being subjected to series of washing and other liquid treatments, the cakes are centrifugally extracted and placed on trays, pallets, rods or other devices which may be loaded onto a platform or racks and transported to a dryer. When it is desired to transfer the cakes from one piece of equipment to another, particularly when liquid treatment stations are positioned at some distance from each other within a plant, the cakes are loaded onto wooden trays of open construction. In storing the cakes on such trays, the cakes are subjected to considerable evaporation and are supported in such a manner as to be frequently abraded by another tray or the cakes supported thereon. When it is necessary to hold the cakes for substantial periods between successive treatments, the cakes are inclined to dry unevenly and subsequently absorb the liquid from the later treatments in a non-uniform manner.

In addition to the damage from abrasion to which the cakes are subjected and the lack of susceptibility to uniform treatment of cakes handled on wooden trays, such trays entail considerable maintenance cost and involve the handling of a great deal of weight per unit weight of strand packages when the relative weights of the trays and the packages is compared.

An object of the invention is to provide a container or tray which is sufficiently enclosed to prevent or substantially inhibit the circulation of air or other gas which might carry water vapor or other volatile liquid from the strand packages supported thereby. It is another object to provide trays or receivers for supporting and protecting rayon cakes from dust or other contaminants in the atmosphere between processing steps and to shield the cakes from abrasion which might result from improper manipulation in the handling of conventional trays and cakes supported thereby. Still another object is to provide trays which are lighter than those of wooden construction now being extensively used. Other

2

objects, features and advantages will be apparent from the following description of the invention and the drawing relating thereto in which

Fig. 1 is an elevation view of two trays and packages supported by the lower tray with portions cut away;

Fig. 2 is an elevation in section of the two trays taken along line II—II of Fig. 1;

Fig. 3 is a pictorial view of one of the trays shown in Figs. 1 and 2;

Fig. 4 is a fragmentary section of a portion of the tray containing a finger-gripping depression;

Fig. 5 is another fragmentary section illustrating another arrangement for manually gripping the tray; and

Fig. 6 is still another fragmentary section analogous to Figs. 4 and 5, illustrating still another finger-grip.

According to the invention, a plurality of box-shaped trays each comprising substantially vertical side walls connected by their top portions to the periphery of a corrugated floor of which each valley of arcuate contour is large enough and sufficiently spaced from adjacent parallel valleys to accommodate a row of cakes placed in each valley. The side walls of each tray are of sufficient height (at least twice the radius of curvature of the arcuate valleys) and the lower edges are of such contour as to mate with the upper edges of another similar tray on which the first tray is unsupported so that cakes supported on the lower tray are enclosed and do not come into contact with the walls and bottom surface of the floor of the overhead tray.

Fig. 1 illustrates two identical trays 8 and 9. The tray 9 supports a plurality of annular cakes 10 on the floor or deck 11 suspended between walls 13 and 14. The tray 8 is adapted in the same manner to support cakes on its floor 16, but as illustrated in Figs. 1 and 2, is used as a cover to prevent or inhibit evaporation of liquid from the cakes of tray 9. The tray 8 may be readily used to support the cakes in the event another tray is supported on the top thereof. A series of trays constructed similarly to trays 8 and 9 may be stacked to any practical height.

Trays according to the present invention may be constructed with any number of cake-aligning grooves or valleys in the floor of the tray of any length deemed expedient. The grooves as shown, are of arcuate contour and spaced to provide clearance between the cakes when the trays are loaded so that it is not necessary for cakes being placed on or removed from the trays to come into contact with or be abraded by other cakes al-

ready in position on the trays. As shown in Fig. 1, the depth of the valleys of the floor 16 below the periphery thereof is sufficiently shallow to expose substantial portions of the circular open regions within the cakes 10 above those walls connected to the floor periphery at the opposite ends of the valleys. That is to say, the depth of the valleys just referred to is less than the sum of the radius of the outer surfaces of the cakes and the radius of the inner surfaces thereof. The raised portions of the floor between the valleys are shown at a level disposed well above the floor periphery at the ends of the valleys.

The trays may be constructed in any manner to give the approximate shape illustrated in the embodiment herein described. As shown, each tray comprises three pieces secured together by fasteners such as stainless steel rivets of the type shown. Each tray comprises two end-panels 19 and 20, and an inverted U-shaped section 21. The end-panels 19 and 20 have in-turned peripheral flanges 22 and 23 which give the panels a generally square and dished conformation. The third section 21 to which the panels 19 and 20 are secured comprises the walls 13 and 14 and the floor 16 which is molded in such a manner as to have two continuous edges at opposite sides of the section which have the same shape as the peripheral flanges along three sides of the panels 19 and 20. The lower edges 17 of the walls 13 and 14 are rounded to provide reinforcement of the walls. To obtain still more rigidity metallic rods 17a and 18a may be molded within the rolled edges 17 and corresponding rolled edges 18 of the tray 8. The flanges of the panels and the opposite edges of the section 21 may be secured together by any suitable means such as rivets 25.

As shown in Figs. 1 and 2, the end walls 19 and 20 of the identical trays 8 and 9 have inturned edges which provide upwardly facing surfaces and downwardly facing surfaces. The downwardly facing surfaces of the upper tray engage the upwardly facing surfaces of the lower tray when the trays are stacked as illustrated and the side walls 13 and 14 of the trays extend into overlapping relationship to substantially enclose the region overlying the floor of the lower tray from the atmosphere. As shown, inwardly facing surfaces along the lower edges of the walls 13 and 14 of the upper tray overlap or engage outwardly facing surfaces along the upper edges of the walls 13 and 14 of the lower tray. Thus, each tray has an upper periphery and a lower periphery of mating configuration, the upper periphery comprising the upwardly facing surfaces of one pair of opposite walls, and the outwardly facing surfaces of the other pair of opposite walls; the lower periphery comprises the downwardly facing surfaces of one pair of opposite walls, and the laterally inwardly facing surfaces of the other pair of walls. Within a plurality of such trays the upper periphery of each tray is adapted to receive the lower periphery of any one of the other trays whereby they may be stacked one on top of the other. Since the end walls of stacked trays shown are disposed in abutting relationship, the side walls are necessarily greater in height than the end walls to provide the overlapping relationship of the side walls shown.

The panels and the section 21 are molded from any desired light-weight high-strength material. Materials found very satisfactory for

the fabrication of the tray sections are glass fabric or fiber and a binder for the fibrous material consisting of an intermediate condensation product of phthalic acid and allyl alcohol. The fibrous material containing the binder is then subjected to a molding and heat-treating procedure in suitable molds to produce the rigid panels 19 and 20 and the section 21.

However, substitutions are readily made for the materials just named. Paper, or fibers such as cotton, nylon, fiber, hemp, asbestos, or other relatively non-plastic fibers in the form of mats, felts, fabrics or webs may be used in place of the glass fabric. The phthalic acid-allyl alcohol condensation product may be replaced by other polyesters prepared by reacting an acid such as maleic acid, fumaric acid, phthalic acid or itaconic acid with an alcohol or a glycol such as allyl alcohol, ethylene glycol or diethylene glycol. Unsaturated hydrocarbons such as styrene or cyclopentadiene may be included in commercially prepared reaction mixtures of this type. Many other chemically-resistant materials in common use as binders in the laminating art and suitable for the purposes of the present invention include the acrylic and methacrylic resins, heat-hardenable silicone resins of the polyorganosiloxane and polysiloxane type, amino resins such as urea-formaldehyde, and melamine-formaldehyde types, phenol-formaldehyde and phenol-furfural resins.

Figs. 4, 5 and 6 illustrate alternative arrangements for manually gripping the trays. Fig. 4 illustrates a pocket 30 molded into a panel such as panels 19 and 20 of Figs. 1 and 2. This construction is resorted to in case it is desired to reduce the escape of vapor from the tray content to a minimum.

Fig. 5 illustrates a simple slot or aperture 32 formed through the wall of a panel 20b similar to those of Figs. 1 and 2. These slots occur at a level of approximately the same elevation as the tops of the cakes contained on the next lower tray when a plurality of loaded trays are stacked. Such slots may be desirable in some instances to allow some vapor to escape from the interior atmosphere of the trays so as to avoid excessive condensation on the interior surfaces thereof.

Fig. 6 illustrates a small cup-shaped molding 34 which may be secured as by rivets to the panel 20b to aid in closing off the interior of the tray from the atmosphere.

While preferred embodiments of the invention have been shown and described, it is to be understood that changes and variations may be made without departing from the spirit and scope of the invention as defined in the appended claims.

We claim:

1. Apparatus for storing annular strand packages and substantially enclosing them from the atmosphere comprising a plurality of similar trays, each tray having two side walls and two end walls and a floor for supporting a plurality of packages, said floor comprising a plurality of arcuate valleys of approximately similar depth and radius of curvature, the valleys extending in parallel relationship in a longitudinal direction toward and away from the end walls, said walls having a height of at least twice said radius of curvature and being joined along their top portions to the periphery of the floor to completely enclose a region underneath the floor, said radius of curvature being equal to or greater than the radius of the exterior surfaces of the packages,

the axes of said arcuate valleys extending transversely above the upper edges of the end walls, the upper periphery of each tray comprising upwardly facing surfaces on one pair of opposite walls and outwardly facing surfaces on the other pair of walls of the tray, the lower periphery comprising downwardly facing surfaces on one pair of opposite walls and inwardly facing surfaces on the other pair of walls of the same tray, the upper periphery of each being of mating configuration with its lower periphery adapting one tray to be placed on top of another with the lower periphery of the upper tray in mating relationship with the upper periphery of the adjacent lower tray, the walls of adjacent trays when stacked one on top of the other being contiguous and having said upwardly and downwardly facing surfaces in abutting relationship and said inwardly and outwardly facing surfaces in overlapping relationship thereby substantially enclosing the package-supporting floors of all trays except that of the top tray in the stack from the atmosphere.

2. Apparatus as defined in claim 1 wherein said

upwardly facing surfaces and said downwardly facing surfaces of each tray are surfaces of the end walls, and the side walls are greater in height than the end walls.
